UNITED STATES PATENT OFFICE

MICHAEL CHARLES LO BOVES, OF RIDGEFIELD PARK, NEW JERSEY, ASSIGNOR TO
UNITED PIANO STRING COMPANY, OF NEW YORK, N. Y., A CORPORATION OF NEW
YORK

PIPE CLEANER

Application filed November 28, 1928. Serial No. 322,570.

The object of this invention is to provide a new and improved pipe cleaner, by which obstructions or dirt can be removed from a waste or sewer pipe.

5 The invention is illustrated in the accompanying drawing, in which—

Figure 1 is an elevation illustrating the device in use in a kitchen sink waste pipe.

Figure 2 is an enlarged view of the cleaner, 10 and

Figure 3 is a partial elevation illustrating a modification.

The device consists of a wire A, one end of which is bent to form a prong or hook B, and 15 the other end of which is bent to form a handle which may be a loop C, as shown in Figure 2, or a transverse section C', as shown in Figure 3.

A short wire D is coiled on the main wire 20 A near the prong thereof and has a free end bent to form a prong or hook E opposing the prong or hook B.

A supplemental wire F is coiled tightly around the main wire A so that the main and 25 supplemental wires are tied or locked together. This tight coiling of the supplemental wire around the main wire prevents the device from kinking when in use; and as the two wires cannot shift or move relatively to 30 each other, the supplemental wire cannot slip to interfere with the handle or the prongs, and the device can be easily cleaned or wiped after use as very little, if any, moisture can get inside the coils of the supplemental wire.

35 If a waste pipe is plugged, the drain at the entrance is removed and the cleaner is inserted down in the pipe as far as it will go. Then it is twirled around and after a few minutes twirling it is pulled out. Whatever substance 40 has been clogging the pipe will adhere to the prongs and thus can be removed. The cleaner is wiped off and the operation is repeated until the pipe is cleared and functions properly. Thus, a simple, efficient and cheap article is provided for the purpose stated.

Having thus fully described my invention, what I claim as new and desire to secure by Letters Patent is:

50 A pipe cleaner comprising a main wire having one end bent to form a prong or hook,

and the other end bent to form a handle, a short wire coiled on the main wire near the prong thereof and having a free end bent to form an opposing prong or hook, and a supplemental wire coiled tightly around the main wire so that the main and supplemental wires are tied or locked together for the purposes stated.

55 In testimony whereof I have hereunto affixed my signature.

60 MICHAEL CHAS. LO BOVES.
